UNITED STATES PATENT OFFICE.

AMBROSE T. MATTHEWS, OF WORCESTER, MASSACHUSETTS, ASSIGNOR TO
THE MATTHEWS MANUFACTURING COMPANY, OF SAME PLACE.

DESIGN FOR A TOP OR CAP FOR KNOBS.

SPECIFICATION forming part of Design No. 30,438, dated March 28, 1899.

Application filed March 4, 1899. Serial No. 707,803. Term of patent 7 years.

To all whom it may concern:

Be it known that I, AMBROSE T. MATTHEWS, a citizen of the United States, residing at Worcester, in the county of Worcester and State of Massachusetts, have invented a new and useful Design for Tops or Caps for Knobs, of which the following is a specification.

The invention has special reference to a design for the tops or caps used in making sheet-metal knobs.

The design is illustrated in the accompanying drawings, in which—

Figure 1 is an elevation, and Fig. 2 is a plan. A top or cap for knobs embodying my de-

sign is characterized by having a plain ring-section 10, a corrugated ring-section 11, and a plain small spherical center section 12.

What I claim, and desire to secure by Letters Patent, is—

The design for a top or cap for a knob as shown and set forth.

In testimony whereof I have hereunto set my hand in the presence of two subscribing witnesses.

AMBROSE T. MATTHEWS.
